(57) **CLAIM**

The ornamental design for a lollipop support apparatus, as shown and described.

DESCRIPTION

FIG. 1 is a front elevation view of a lollipop support apparatus with a broken line segments indicating no particular length of the lollipop support apparatus;

FIG. 2 is a rear elevation view of the lollipop support apparatus also with a broken line segments indicating no particular length of the lollipop support apparatus;

FIG. 3 is a side elevation view of the lollipop support apparatus again with broken line segments indicating no particular length of the apparatus;

FIG. 4 is a top planar view of the lollipop support apparatus;

FIG. 5 is a bottom planar view of the lollipop support apparatus;

FIG. 6 is a perspective view of the lollipop support apparatus with the broken line segments indicating no particular length of the lollipop support apparatus;

FIG. 7 is a front elevation view of the lollipop support apparatus including the lollipop product supported by the apparatus;

FIG. 8 is a front elevation view of a single segment of the lollipop support apparatus shown separately for ease of illustration;

FIG. 9 is a rear elevation view of the single segment of the lollipop support apparatus shown in FIG. 8;

FIG. 10 is a side elevation view of the single segment of the lollipop support apparatus shown in FIG. 8;

FIG. 11 is a top planar view of the single segment of the lollipop support apparatus shown in FIG. 8; and,

FIG. 12 is a bottom planar view of the single segment of the lollipop support apparatus shown in FIG. 8.

The broken lines shown in FIGS. 1–12 are for illustrative purposes only and form no part of the claimed design.
